UNITED STATES PATENT OFFICE.

NORMAN McCARTY, OF INDIANAPOLIS, INDIANA, ASSIGNOR TO ATLAS ENGINE WORKS,
OF INDIANAPOLIS, INDIANA, A CORPORATION OF INDIANA:

PUMP.

940,704.

Specification of Letters Patent. Patented Nov. 23, 1909.

Application filed June 14, 1909. Serial No. 502,044.

To all whom it may concern:

Be it known that I, NORMAN McCARTY, a citizen of the United States, residing at Indianapolis, in the county of Marion and State of Indiana, have invented certain new and useful Improvements in Pumps, of which the following is a specification.

The object of my invention is to produce a pump mechanism by means of which measured quantities of liquid (of variable amount) may be successively discharged therefrom, provision being made for controlling the measuring mechanism by means of a speed controlled governor.

The apparatus is especially designed for use in conjunction with an internal combustion engine of the non-explosive type, wherein it is desirable to deliver accurately measured, but varying, successive quantities of fuel to the combustion chamber of the engine.

The accompanying drawing, which is an elevation in partial section, illustrates an embodiment of my invention.

In the drawings, 10 indicates a suitable main body in which is formed a pump chamber 11. Leading into said pump chamber is an inlet passage 12 controlled by an inwardly opening valve 13 the stem of which is projected through a suitable packing gland 14 and provided with a head 15 beneath which is arranged a light spring 16 which serves to normally close the valve. Leading from chamber 11 is a discharge pipe 17 in which is preferably mounted an outwardly opening check valve 18. Projected into chamber 11 through a suitable packing gland 21 is a displacing plunger 22. In order to operate the plunger 22 I provide a lever 25 the fulcrum 26 of which is movably mounted in a guide-way 27 formed in bracket 28. Fulcrum 26 is also projected into a slot 31 formed in lever 25 so that, by moving the fulcrum, the two arms of the lever 25 may be simultaneously varied. Fulcrum 26 may be shifted by any desired means, and in the form shown in the drawings said fulcrum is connected by a link 32 with a bell-crank lever

33 which, in turn is connected to a speed controlled governor 34. Lever 25 is connected to a driving arm 41 which is provided with an adjustable pin 35 adapted to engage head 15, the said pin thus having a

constant uniform stroke and being adjustable toward and from the head 15.

The operation is as follows: With the parts in the positions shown in the drawing, plunger 22 has had half of its inward stroke and pin 35 has just left head 15, so that valve 13 has just seated. The further downward movement of plunger 22 will serve to eject liquid from chamber 11 into pipe 17. On the outward stroke of plunger 22, liquid will be drawn into chamber 11 past valve 13, by the suction of said plunger the spring 16 being light and yielding to such suction, and, during this outward stroke of plunger 22, pin 35 will be brought down into engagement with head 15 so as to positively open valve 13. On the return or inward stroke of plunger 22 the valve 13 will be held open by pin 35 until plunger 22 had made half of its inner stroke so that, before there is any discharge from the pump chamber into pipe 17, there will be a back flow of a portion of the liquid through or past the inlet valve 13.

In the particular structure shown, fulcrum 26 is at its farthest possible point to the left and the pump in this position is giving its maximum discharge. By elongating the slot 31 to the left and shifting fulcrum 26 still farther to the left, the time during which valve 13 would be held open by pin 35 would be still further decreased relative to the stroke of piston 22, and the discharge of the apparatus into pipe 17 would be correspondingly increased. By shifting fulcrum 26 to the right, the arm of lever 25 which is connected to plunger 22 is shortened, while the opposite arm of said lever is lengthened, and the consequence will be that the total stroke of plunger 22 will be decreased.

Where the variation of delivery of a pump is obtained by the variation of the stroke of a displacing plunger, the plunger being driven by means of a variable arm lever, as shown in drawing, it is mechanically difficult to produce a structure in which the adjustable parts bear such relation to each other that the ejecting stroke of the plunger can be reduced to zero and it is for this reason that I have provided a means for holding the inlet valve open during a part of the return or ejecting stroke of the plunger so that, by a proper adjustment of the pin 35 relative to head 15, when fulcrum 26 is ad-

justed so as to produce a minimum stroke of the ejecting plunger 22, valve 13 will be held open during the entire ejecting stroke of the plunger and there will be no ejection of liquid from the pump chamber. If, however, the operation of the engine, which is to be supplied with my pump, is such as to require a fixed minimum amount of fuel at each stroke of the pump, in order to keep 10 the engine running either with no load or with a minimum load below which the requirements never pass, the adjustment of pin 35 relative to head 15 will be such that, when the ejecting piston 22 has its shortest 15 stroke, valve 13 will be closed just in time to permit an ejection of the minimum required amount of fuel. The additional requirements are then provided for by the adjustment of fulcrum 26 in the manner already 20 described.

I claim as my invention:

1. In a pump comprising a main chamber having an inlet and an outlet, a valve arranged in said inlet, an ejecting plunger associated with the pump chamber, means for varying the ejecting stroke of the plunger between maximum and a minimum greater than zero, and means for holding the inlet valve open during a portion of the ejecting 25 stroke of the plunger substantially equal to or less than the difference between its minimum ejecting stroke and zero.

2. In a pump comprising a main chamber having an inlet and an outlet, a valve arranged in said inlet, means for normally holding said valve closed, a plunger projectable into the pump chamber, means for varying the stroke of said plunger, and means for holding the valve open during a portion of the ejecting stroke of the plunger. 35

3. In a pump comprising a main chamber having an inlet and an outlet, a valve arranged in said inlet, a plunger projectable into the pump chamber, a lever connected

with said plunger, means for varying the stroke of said lever to vary the stroke of the plunger, and means for engaging the inlet valve and holding same open during a portion of the ejecting stroke of the plunger. 45

4. In a pump comprising a main chamber 50 having an inlet and an outlet, a valve arranged in said inlet, means for normally holding said valve closed, a plunger projectable into the pump chamber, a lever connected with said plunger, means for varying the stroke of said lever to vary the stroke of the plunger, and means for engaging the inlet valve and holding same open during a portion of the ejecting stroke of the plunger. 55

5. In a pump comprising a main chamber 60 having an inlet and an outlet, a valve arranged in said inlet, a plunger projectable into the pump chamber, a lever connected with said plunger, a fulcrum for said lever movable relative thereto to vary its effect 65 upon the plunger, means for shifting said fulcrum relative to the lever, and means for holding the said inlet valve open during a portion of the ejecting stroke of the plunger.

6. In a pump comprising a main chamber 70 having an inlet and an outlet, a valve arranged in said inlet, a plunger projectable into the pump chamber, a lever connected with said plunger, a fulcrum for said lever movable relative thereto to vary its effect 75 upon the plunger, means for shifting said fulcrum relative to the lever, means for normally closing the inlet valve, and means for holding the said inlet valve open during a portion of the ejecting stroke of the plunger. 80

In witness whereof, I have hereunto set my hand and seal at Indianapolis, Indiana, this fourth day of June, A. D. one thousand nine hundred and nine.

NORMAN McCARTY. [L. S.]
